BLADE FOR A VEHICLE WINDSHIELD WIPER

Edward Rickett, 7355 S. Elait St., Littleton, Colo. 80120

Filed Jan. 22, 1968, Ser. No. 10,239

Term of patent 14 years

U.S. Cl. D14—6
Int. Cl. D12—14

FIG. 1

FIG. 2

FIG. 3

FIG. 4

FIG. 5

FIG. 1 is a perspective, cutaway, to indicate an indeterminate length, view embodying one form of a blade for a vehicle windshield wiper of my design;

FIG. 2 is a top plan view, also cutaway, of the embodiment of FIG. 1;

FIG. 3 is an end view of another form of the blade for a vehicle windshield wiper of the invention;

FIG. 4 is an end view of a further form of the blade for a vehicle windshield wiper of the invention; and

FIG. 5 is an end view of a still further form of the blade for a vehicle windshield wiper of the invention.

I claim:

The ornamental design for a blade for a vehicle windshield wiper, substantially as described and shown.
